MECHANICAL CALENDAR

Elden L. Hostetler, Pomona, Calif., assignor of
one-third to William G. Gleason, Pomona,
Calif., and one-third to Archie D. Mitchell,
Ontario, Calif.

Application July 7, 1938, Serial No. 218,002

1 Claim. (Cl. 40—117)

The invention relates to improvements in mechanical calendars of the general type in which advanceable exhibiting means is provided to show the dates and preferably to show also the day names and the month names, and in which a clock train or other chronometric mechanism acts as part of the operating means for the exhibiting means.

The exhibiting means includes one or more webs, ribbons or tapes to be intermittently moved in such manner as to be unwound from one rotatable member and simultaneously wound on another rotatable member, and one of the foremost objects of the invention is to make novel provision whereby the tape or the like may be so fed and the two rotatable members so turned at the proper relative speeds, to both prevent slack in said tape or the like and to prevent excessive tension thereon, even though the amount of tape on the one rotatable member is gradually increasing and that on the other rotatable member gradually decreasing.

A further object of the invention is to provide a unique means for actuating the tape-feeding means only every twenty-four hours, the change preferably taking place between eleven p. m. and one a. m.

A still further object is to provide a novel construction which may be easily set back and readjusted at the end of any year and may be made to take care of the twenty-ninth day occurring in February during leap years.

A still further object is to provide a construction which will be comparatively simple and inexpensive and will nevertheless be reliable and durable.

With the foregoing and minor objects in view, the invention resides in the novel subject matter hereinafter described and claimed, description being accomplished by reference to the accompanying drawings.

Fig. 1 is a front elevation partly broken away and in section showing a calendar clock embodying the invention.

Figs. 2 and 3 are horizontal sectional views on lines 2—2 and 3—3 respectively of Fig. 1.

Fig. 4 is a detail vertical section on line 4—4 of Fig. 1.

Fig. 5 is a diagram showing the parts in readiness to start advancing the calendar at 11 p. m.

Fig. 6 is a view similar to Fig. 5 but showing the relation which exists after the calendar has been advanced one step, this relation existing at 1 a. m.

Fig. 7 is a view similar to Figs. 5 and 6 but showing the tappet wheel, at 11 a. m., in readiness to again move but without effecting any advance of the calendar.

Fig. 8 is a view similar to Figs. 5, 6 and 7 but showing the relation which exists at 1 p. m.

Fig. 9 is a detail sectional perspective view showing a modification.

In the drawings above briefly described, a preferred construction has been illustrated, and while this construction will be rather specifically explained, it is to be understood at the outset that variations may be made within the scope of the invention as claimed.

Suitably mounted in a casing C, preferably a clock casing, are two shafts 10 and 10' both 10 of which may rotate, preferably with a sufficient degree of friction to securely hold them against accidental rotation from any position to which they may be turned. Tape of metal, fabric or other preferred material or materials, is wound 15 partially on the shaft 10 and partially on the shaft 10'. In the present disclosure, the tape just mentioned consists of three separate tapes 11, 12 and 13, and each shaft is provided with three spool portions 14, 15 and 16 for said tapes 11, 12 20 and 13, respectively. While normally the three spool portions 14, 15 and 16 of either shaft 10 or 10' rotate bodily as a single unit, the spool portions 14 of said shafts are secured to the latter by set screws or the like 17, allowing rotative 25 adjustment of said spool portions 14 with respect to the portions 15 and 16 when the calendar is to be adjusted at the end of the year or the beginning of the next, according to the day on which the new year starts. One end of the shaft 30 10' is suitably shaped as at 18 for engagement with a key (not shown) by means of which the tapes 11, 12 and 13 may be reset for the new year, all the spool portions 14, 15 and 16 then rotating bodily as a single unit. After this re- 35 setting, however, the set screws 17 are loosened to permit any necessary relative adjustment of the tapes to initially set the calendar. The tape 12 displays the week day names (Monday, Tuesday, Wednesday, etc.) and the tape 11 displays 40 the months and the dates (January 1, January 2, January 3, etc.; February 1, February 3, etc.). For the month of February, I may provide either the dates which said month contains in ordinary years (1 to 28) or the dates which February 45 contains in leap years (1 to 29). If twenty-eight dates be allotted to February, every leap year the mechanism must be set back one step on February 29. Otherwise, on February 29th, it would show March 1st. If twenty-nine dates 50 be allotted to February, in years which are not leap years, the mechanism must be advanced one step on March 1st. Otherwise, it would show February 29th instead of March 1st. Setting back one step or advancing one step, according 55 to the number of dates allotted to February, may be readily accomplished by hand.

A continuous belt 19 is trained around the portions of the tape 13 wound on the shafts 10 and 10', said wound tape portions being specifically 60

designated at 13^a and 13^b. These wound tape portions 13^a and 13^b constitute pulleys cooperable with the belt 19, the diameter of one of said pulleys gradually decreasing and that of the other 5 gradually increasing as the two shafts are turned to wind the tapes 11, 12 and 13 from one shaft to the other. The "pulleys" 13^a and 13^b thus serve to insure proper relative speeds of the two shafts to allow unwinding of the tapes from one 10 shaft and simultaneous winding on the other shaft, without permitting any slack in said tapes and without exerting undue tension thereon. Also, the feeding means which effects turning of the two shafts, directly coacts with the belt 19 15 and every twenty-four hours moves this belt only to a predetermined extent, it thus being insured that the tapes 11 and 12 shall move to the same extent. In order to obtain this result, it is of course necessary that all of the tapes be wound 20 unidirectionally on the spool portions 14, 15 and 16 of the shaft 10 and that said tapes be wound unidirectionally on the spool portions of the shaft 10'. It is also necessary that all of the wound 25 tape portions on the shaft 10 bear the same relation with all of the wound tape portions on the shaft 10'. In other words, if the wound portion of one tape on the shaft 10 at any one time, be one-half the diameter of the wound portion of the same tape on the shaft 10', it is necessary 30 that this same relation exist between the wound portions of the other tapes.

The feeding means preferably comprises a pawl 20, a lever 21 to which said pawl is pivoted, and a spring 22 for normally holding said lever 35 in the position shown in Fig. 1. Any desired provision may be made whereby the pawl 20 engages the belt 19 each time said pawl is moved in one direction and whereby said pawl will free said belt each time it is moved in the other direction. If the belt 19 be of metal construction, it may be provided with spaced notches 23 for engagement with the lateral end 24 of the pawl 20.

A tappet wheel 25 is provided to move the lever 40 or actuator 21 every twenty-four hours, to so operate the pawl 20 as to advance the tapes 11, 12 and 13 one notch or step, and when the movement of said lever or actuator in this manner has 45 been completed, the star wheel 26 frees said lever or actuator and the spring 22 returns it to its normal position in readiness for the next operation. As the hour wheel 26 of a clock or similar chronometric mechanism may best be used in operating the tappet wheel 25, I have 50 disclosed such an arrangement. The wheel 26 makes one complete revolution in twelve hours and drives a master tappet 27 at the same speed. This master tappet 27 is cooperable successively with all of the tappets 28 and 29 of the tappet 55 wheel 25 to turn this tappet wheel one step each twelve hours. However, as it is not intended that the tappet wheel 25 shall operate the lever 21 every twelve hours, I so construct said tappet wheel 25 that only its alternate tappets 29 can 60 operate said lever, the intervening tappets 28 being so related with said lever that they will always clear the same. In the present disclosure, the tappets 28 and 29 are in the form of radiating arms, the tappet 29 being sufficiently 65 long to strike and operate the lever 21, and the tappets 28 being sufficiently short to clear said lever.

Figs. 5 to 8 diagrammatically show the manner in which the elements 26, 27, 25, 21 and 20 70 act to move the belt 19 and advance the tapes 11, 75

12 and 13, one step or notch each twenty-four hours. The advance preferably starts at 11 p. m. as shown in Fig. 5. At this time, the tappet 27 driven by the wheel 26, has come in contact with one of the tappets 28 of the tappet wheel 25, and one of the tappets 29 of said wheel 25 is ready to move the lever 21. Between 11 p. m. (Fig. 5) and 1 a. m. (Fig. 6), the tappet 27 has turned the tappet wheel 25 one step and said tappet wheel has operated the lever 21 to 10 advance the tapes to show the date, etc. for the new day. Just as soon as the tappet 29 which has operated the lever 21 clears said lever, the spring 22 restores the latter to its normal position, placing the pawl 20 in readiness for the next 15 operation. At 11 a. m. (Fig. 7), the tappet 27 has come in contact with one of the tappets 29 of the wheel 25 and turning of said wheel 25 is therefore started, but during this turning, one of the tappets 28 of said wheel 25 merely clears 20 the lever 21 without operating this lever to advance the tapes. By 1 p. m. (Fig. 8), the movement of the tappet wheel 25 has ceased and one of its tappets 29 is then in readiness to operate the lever 21 when said wheel 25 is next turned. 25 This next turning starts again at 11 p. m. (Fig. 5) and ceases at 1 a. m. (Fig. 6), as previously.

In the diagrammatic figures above referred to (Figs. 5 to 8), the hour and minute hands and the dial of a clock have been conventionally 30 shown and this is true also of Fig. 1. It is to be understood, however, that while the invention is preferably associated with a clock, this is not absolutely essential, for any adequate chronometric mechanism could be employed for purposes of operation.

It may be further explained that while a separate tape 13 which I preferably term a filler tape, is in most instances desired for coaction with the belt 19, the equivalent of said filler tape 40 could well be constituted by one longitudinal portion 13' of an exhibiting tape 12^a, as seen in Fig. 9. Both in this modification and in the main form of construction, tape is wound partially on the shaft 10 and partially on the shaft 45 10', and the belt 19 is trained around portions of the tape wound on said shafts.

While a tappet wheel 25 has been shown of the radial arm type, one of the lateral pin type 50 might well be used instead.

As excellent results may be obtained from the general construction shown and described, it is 55 preferably followed. However, numerous variations may be made within the scope of the invention as claimed.

I claim:

In a mechanical calendar or similar mechanism, two parallel rotatably mounted shafts each having two spool portions fixed with respect to each other and a third spool portion rotatively adjustable with respect to said two spool portions, three tapes wound partially on the spools of one shaft and partially on the spools of the other shaft respectively, the tape on said third spool portions and one of the other tapes having 60 week day names and month names and dates respectively, a belt trained around the wound portions of the other tape, feed means cooperable with said belt for feeding the latter step-by-step, and operating means for said feed means, 65 the diameters of the tape portions wound on one of said shafts all having the same relation with the diameters of the tape portions wound on the other of said shafts.
